HINGE

Robert S. Wagner, Milwaukee, Wis., assignor to
 E. E. Wagner Manufacturing Company, Milwaukee, Wis., a corporation of Wisconsin

Application November 18, 1944, Serial No. 564,017

3 Claims. (Cl. 16—159)

1

This invention relates to improvements in hinges, particularly of the types which are self-secur ing upon being applied, and to the method of applying such hinges to the members which are to be hinged.

While it is desirable from the point of view of strength and appearance to insert or imbed the leaves of a hinge into the bodies of the members to be hinged and hold such leaves by friction, certain disadvantages exist which heretofore have offset such desirability. In the first place, it is difficult to hold the hinge and properly insert the leaves under pressure, at least without using numerous and time-consuming steps in the process. Secondly, in order to permit the members to swing apart, one edge of a member must be provided with a continuous rabbet which is unsightly as well as costly to provide.

One of the objects of this invention is, therefore, to provide a hinge which may be quickly applied to the members to be hinged and securely fastened without the use of separate fastenings.

Another object of the invention is to provide a hinge which can be used to hinge two members in edge-to-edge relation without requiring a continuous rabbet in an edge of one or both of the members.

A further object is to provide a hinge which can be applied in one operation to both members to be hinged.

A still further object is to provide a method for holding the hinge so that both members to be hinged may be applied simultaneously to the hinge.

The foregoing objects are accomplished by inserting a backing-up tool between the leaves of the hinge in such a manner that the frictional engagement therebetween will hold the hinge on the tool, and forming from said leaves, adjacent the pintle bearing, oppositely projecting securing portions. It is preferable to secure the leaves to the pintle so that when in substantial parallel superimposed position they are spaced to flatly receive therebetween and frictionally engage the flat end of the backing-up tool. The securing portions are provided with a number of protruding barbs which frictionally engage the sides of routings formed in the edges of the members to be hinged. The frictional engagement between the leaves and the tool will hold the hinge on the tool so that the members to be hinged can be pressed simultaneously into the substantially aligned securing portions. By arranging the spacing of the routing from the outer surface of the members to be hinged, the pivotal axis of the

2

hinge can be placed so that the amount of the opening or backward swing of the hinged members can be controlled. Instead of the continuous rabbet usually required, there need be only a mortise sufficiently large to accommodate the leaves and pintle bearing of the hinge. The leaves thus perform two functions. They provide a bearing surface whereby the hinge can be mounted on a backing-up tool for insertion, and they position the pintle pin and axis sufficiently near one edge of the members to permit them to swing apart without the use of a continuous rabbet in one or both edges of those members.

With the foregoing and other objects in view, 15 developed by the following description, the invention consists in certain novel advantageous structural organizations and features, as well as combinations and sub-combinations, as more fully explained hereinafter and specified by the 20 following claims.

Referring to the accompanying drawing forming a part hereof, Figure 1 is an enlarged fragmentary view in front elevation of a hinge embodying the instant invention. For the sake of 25 clarity the hinge has been shown inserted in hinged members, a sectional view being taken on the meandering line 1—1 of Fig 2;

Figure 2 is a sectional view taken on the line 2—2 of Figure 1 with certain portions of the 30 hinged members removed;

Figure 3 is a sectional view of a box and cover with a hinge embodying the instant invention inserted in and secured to the box and the cover to hinge these members, and a view in side elevation of the backing-up tool used in inserting the hinge;

Figure 4 is a fragmentary sectional view of the hinge showing a slight modification; and

Fig. 5 is a perspective view of the hinge having the slight modification shown in Fig. 4.

Without intending to so limit the application of the hinge embodying the instant invention, it is shown as an example inserted in and secured to the body 1 and the top 2 of a wooden box 3 of the type used for containing jewelry and other small personal objects. In this example a mortise 4 is made in the edge of the back of the body portion 1 and accommodates the pintle bearing of the hinge. Both backs of the body 1 and top 2 are provided with vertically positioned and aligned routings 5 into which the respective leaves of the hinge are inserted. This routing may be prepared by a small circular saw having a thickness less than the thickness of the leaf of the hinge.

The hinge comprises two leaves designated respectively 6 and 7 which are pivotally interconnected by a pintle 8 and preferably arranged so that when the leaves are in substantial parallel superimposed position (as shown in Figure 2) they will be spaced to receive and flatly engage the end of a backing-up tool. This is accomplished by forming the pintle barrels of each leaf so as to be substantially tangential to the leaf. Hence when the leaves 6 and 7 are in the parallel relationship shown in the figures they will be spaced by the thickness of the pintle 8. The leaf 6 is provided with a securing portion 9 formed upwardly as shown in Figure 2 from the body of the leaf to assume a position substantially normal thereto. The securing portion 9 is spaced from the pintle or pintle bearing 8 and is provided with protruding barbs 10, the purpose of which will be hereinafter described. One way of forming the securing portion 9 is shown in the modification viewed in Figure 4. A U-shaped outline 11 is cut in portion 9 which causes a tab 11a to remain as an extension of the leaf 6 when the portion 9 is formed upwardly about a line passing through the ends of the U. The leaf 7 also has formed downwardly therefrom, as viewed in Figure 2, a securing portion 12. This portion 12 is also provided with barbs 10 and is positioned substantially in alignment with the securing portion 9, as shown in Figure 2. It, like securing portion 9, may be provided with a U-shaped outline 13 cut therein which leaves a tab 13a as an extension of the body of the leaf 7 when the securing portion 12 is formed downwardly about a line passing through the ends of the U. The tabs 11a and 13a make the junction between the leaves and the securing portions more rigid and also provide additional backing-up tool engaging surfaces. It is preferable to provide the securing portions 9 and 12, respectively, with a small semi-circular projection 14 which acts as a guide finger in inserting the securing portions in the routings 5 of the box members.

As is shown in Figure 3, a backing-up tool 15 is used in assembling the hinge to the box members. This tool is substantially the same width as the width of the respective hinge with which it is used in the application thereof. Its backing-up end (the left end, as viewed in Figure 3) is flat and substantially the thickness of the distance between the inner surfaces of the leaves 6 and 7 when they are in substantially parallel superimposed position. The right hand end, as viewed in Figure 3, of the backing-up tool 15 is made thin so that it will cause only a very slight opening between the front edges of the box. The hinge is frictionally held on the end of the backing-up tool 15 by the flat engagement between the surfaces of the leaves and the tool. In some cases it is advantageous to magnetize the tool to help hold the hinge. By the manipulation of the tool, the hinge can be positioned and held so that each securing portion is in alignment with a respective routing. With the hinge so held, the guiding projections 14 are inserted in the respective routings 5 of the body 1 and top 2 of the box, and these members are thereupon forced together under pressure asserted in opposite directions. This drives each of the securing portions 9 and 12 into the routings, and the barbs 10 frictionally engage with the sides of the routings 5. Thus in one operation the hinge is positioned and rigidly secured in place. If more than one hinge is to be utilized, the tool may be provided with

two or more hinge-engaging portions and both hinges simultaneously secured.

By adjusting the distance of the routings 5 from the outer side of the body 1 and top 2 of the box, the axis of the pintle 8 will be adjusted relative to these sides. With the axis of the pintle positioned as shown in Figure 3, the top of the box can be swung back on the hinge to the position shown in the broken lines, in which position the bottom back edge of the top 2 engages the top back edge of the body 1 and prevents further backward swinging of the top. If it is desired to permit the top to swing further back, it is only necessary to change the positioning of the routings 5, so that the axis of the pintle 8 is moved further to the left, as viewed in Figure 3, thus decreasing the distance between the axis of the pintle 8 and the back edge of the box.

It will be seen from an inspection of the drawings that the box and hinge as assembled present a very neat appearance. At the most, only a small portion of the barrel is visible, and there is a substantial edge-to-edge relationship between the top 1 and bottom 2 broken only by the small mortises 4 necessary to accommodate the barrel of the hinge. The engagement between the securing portions 9 and 12 and their respective barbs 10 with the surfaces of the routings 5 is more than adequate to maintain the hinge rigidly fixed in place. This method of fastening the hinge also eliminates the additional steps of adding other securing devices, such as nails or screws, and also prevents the breaking and cracking of the fibres of the wood or other material usually occurring when additional fastening devices are used.

Although only several embodiments of the invention are shown and described herein, it will be understood that this application is intended to cover such other changes or modifications as come within the spirit of the invention or scope of the following claims.

I claim:

1. In a hinge, a pintle bearing, a pair of leaves secured to said bearing, said leaves when in substantially parallel superimposed position being spaced to substantially flatly receive therebetween and mutually engage the flat end of a backing-up tool, securing portions formed outwardly from each leaf in substantial alignment with each other when said leaves are so positioned, and tabs extending beyond said portions and parallel to said leaves to increase the surface of said leaves adapted to engage the backing-up tool.
2. In a hinge, a pintle bearing, a pair of leaves secured to said bearing, said leaves when in substantially parallel superimposed position being spaced to flatly receive therebetween and mutually engage the flat end of a backing-up tool, securing portions formed outwardly from each leaf in substantial alignment with each other when said leaves are so positioned, tabs extending beyond said portions and parallel to said leaves to increase the surface of said leaves adapted to engage the backing-up tool, and barbs on said securing portions to frictionally engage the material of members joined by said hinge.
3. In a hinge, a pintle, a pair of leaf members pivotally connected thereto with the planes of the respective leaf members substantially tangent to said pintle, whereby the leaf members may be positioned in opposed, spaced, parallel relation, the terminal portion of each leaf member being provided with a laterally extending securing por-

tion co-extensive transversely with the leaf and disposed substantially perpendicular thereto, each of said securing portions being provided with barbs upset from and extending transversely of the plane thereof, said barbs having biting edges directed towards the respective hinge leaves.
